UNITED STATES PATENT OFFICE.

CRANDALL U. NORCROSS, OF WINCHENDON, MASSACHUSETTS, ASSIGNOR TO ALASK FREEZER COMPANY, OF WINCHENDON, MASSACHUSETTS, A TRUST ASSOCIATION.

POWER UNIT FOR DRIVING ICE-CREAM FREEZERS AND OTHER APPLIANCES.

1,418,962.

Specification of Letters Patent. Patented June 6, 1922.

Application filed January 17, 1921. Serial No. 437,903.

To all whom it may concern:

Be it known that I, CRANDALL U. NORCROSS, a citizen of the United States, residing at Winchendon, in the county of Worcester and State of Massachusetts, have invented new and useful Improvements in Power Units for Driving Ice-Cream Freezers and Other Appliances, of which the following is a specification.

10 This invention relates to a compact power unit especially adapted to perform work about the home, farm or small work shop, in a simple and rapid manner which would otherwise require laborious effort.

15 The invention is illustrated and described in this application, as applied to an ice cream freezer and ice crusher, but it may be used with equal facility for driving other appliances.

20 The primary object of the invention is to provide a compact power unit of light weight and simple and inexpensive construction which may be readily set up and adjusted to drive devices of different dimensions.

25 The invention is described in connection with the accompanying drawing, in which:—

Figure 1 is a side view of the invention as applied to an ice cream freezer and an 30 ice crusher with certain parts broken away to more clearly illustrate the invention.

Figure 2 is a side elevation of the same with the ice cream freezer removed.

The numeral 10 designates a supporting 35 table for the power unit, which table is provided with the legs 11 having casters 12 to increase the portability of the power unit. Standards or posts 13 are provided with base flanges 14 which are secured to the table 10

40 by means of fastening devices 15. A bed plate 16 is provided with openings through which the rods 13 are adapted to extend so that the bed plate 16 is slidably mounted upon said posts. About said openings the 45 bed plate 16 is provided with depending annular flanges 17 provided with suitable openings for receiving set screws 18 whereby the bed plate may be maintained in adjusted position upon the posts 13.

50 The bed plate 16 is provided near opposite ends with elevated surfaces 19 and 20. A motor 21 is mounted on the surface 19 and secured to the plate by means of the bolts 22. A gear casing 23 is mounted on the surface 55 20 by means of a bracket 24 having a base

flange which is secured to the bed plate 16 by the bolts 25. The gear casing is provided with a depending arm 26 formed with a threaded aperture 27 adapted to register with an aperture formed in the bracket 24 60 and a bolt 28 passes through said apertures and engages the threads 27 for clamping the arm 26 tightly to the bracket 24. It will be understood that the bracket 24 may be raised or lowered by the insertion of suitable plates or shims 29 between its flanged base and the surface 20, or in lieu thereof, a plurality of spaced apertures (not shown) may be formed in the bracket 24, either one 65 of which may receive the bolts 28 for adjusting the height of the gear housing. Slight adjustments laterally as well as in elevation can be obtained by moving the gear casing pivotally about the bolt 28 and then clamping the arm 26 tightly to the bracket 24 for 70 holding the casing in adjusted position.

The gear or transmission casing 23 contains bearings 31 and 32 for shafts 33, 34 respectively, which shafts are arranged at right angles. The shaft 34 has secured 80 thereto a worm gear 35 meshing with a worm 36 secured to the shaft 33. The shaft 33 is extended beyond one side of the casing and carries at one end, one half, herein designated 36°, of a flexible coupling, the 85 other half 36' being carried on the end of the shaft 37 of a driving motor 21, whereby the shafts 33 and 37 are operatively connected. The shaft 37 has also secured thereto a driving pulley 38.

The shaft 34 is extended in opposite direction from the gear casing 23 and carries at one end the small pulley 39 and has driving connection at the other end with the driving mechanism or gearing of the ice cream 95 freezer 40, said gearing being of the usual form and located within the gear housing 41; the gear housing being clamped to the upper portion of the freezer by means of the clamps 42. A large pulley 43 is secured to the shaft 34 and is connected by means of the belt 44 to the pulley 45 of an ice crusher 46, the latter being secured to the table 10 and provided with a chute 47 which projects beyond the side of the table, so that the 105 crushed ice may be collected in a suitable receptacle placed beneath the exit of said chute.

In assembling the mechanism and assuming that the posts 17 are properly placed and 110

spaced upon the table 10 and that the ice cream freezer 40 and ice crusher 46 are located on the table, the bed plate 16 is then mounted upon the posts and adjusted to 5 the desired position by means of the set screws 18. The motor 21 and bracket 24, with the gear casing 23, are then mounted on the bed plate. In case the shaft 34 does not align with the shaft of the ice cream 10 freezer, the bed plate 16 may be given a finer adjustment and then a more delicate adjustment can be obtained by means of the shims or plates 29 or by pivotally moving the gear casing 23 about the bolt 28. The 15 shaft 34 may now be secured to the driving shaft of the ice-cream freezer and the shaft 33 can be connected to the driving shaft 37 of the motor by means of the flexible coupling 36¹, 36². By means of the belt 44 between the pulleys 43 and 45 the ice crusher is driven and this may be accomplished before the shaft 34 is connected to the driving mechanism of the ice cream freezer or subsequently.

25 Having described my invention, what I claim as new and desire to secure by Letters Patent, is:—

1. A power unit of the class described comprising a supporting device having posts secured thereto, a bed plate slidably mounted on the posts, means for maintaining said bed plate on said posts in adjusted position, a motor and a bracket secured to the bed plate, a gear casing adjustably mounted on the 30 bracket, shafts arranged substantially at right angles and journalled in said casing, gearing connecting said shafts within the casing, one of said shafts being connected to said motor and the other adapted to be 35 directly connected to the driving mechanism of an ice cream freezer, tool or the like.

2. A power unit of the class described comprising a table having posts secured thereto, a bed plate adapted to slide on said 40 posts, means for maintaining said bed plate on said posts in adjusted position, a motor

and a bracket secured to the bed plate, a gear casing adjustably mounted on the bracket, shafts arranged substantially at right angles and journalled in said casing, gearing 50 connecting said shafts within the casing, a flexible coupling connecting the shaft of said motor to one of said shafts the other of said shafts being adapted to be connected at one end to the driving mechanism of an 55 appliance such as an ice cream freezer, tool or the like, and having pulleys mounted thereon for driving other appliances of like character.

3. In a power unit of the class described, 60 the combination of a portable supporting device having posts secured thereto, a bed plate slidably mounted on said posts, means for maintaining said bed plate on said posts in adjusted position, a motor and a transmission gear casing mounted on said bed plate, said casing having shafts journalled therein and projecting therefrom, gearing connecting said shafts within the casing, mounted on said shafts, and a motor connected to one of said shafts, the other of 65 said shafts being adapted to be directly connected to the driving mechanism of a machine or appliance.

4. In a power unit of the class described, 70 the combination of a bed plate, a motor and a bracket secured to said bed plate in spaced relation, a gear casing pivotally adjustable on said bracket, means for locking the casing in adjusted position, shafts journalled 75 in said casing and connected by gearing therein, a motor connected to one of said shafts and means whereby devices may be driven from either of said shafts.

In testimony whereof I have hereunto set 80 my hand in presence of two subscribing witnesses.

CRANDALL U. NORCROSS.
